UNITED STATES PATENT OFFICE.

THOMAS J. PENNINGTON, OF NAUGATUCK, CONNECTICUT.

ORE-TREATING APPARATUS.

1,294,531.

Specification of Letters Patent. Patented Feb. 18, 1919.

Application filed May 24, 1917. Serial No. 170,596.

To all whom it may concern:

Be it known that I, THOMAS J. PENNINGTON, a citizen of the United States, residing at Naugatuck, in the county of New Haven 5 and State of Connecticut, have invented certain new and useful Improvements in Ore-Treating Apparatus, of which the following is a specification.

This invention relates to an improved 10 method for the treatment of metalliferous ores, and more particularly to improvements in apparatus used for the separation of sulfid particles from gangue by what is commonly known as the flotation process.

15 The flotation processes at present in use may be divided into two classes, to-wit, — a class in which the material under treatment is continuously fed into a container and continuously discharged from the same at a 20 fixed ratio, and a class in which the material is fed into a container at regular intervals and permitted to remain during a treatment period of predetermined length.

The processes of the first-mentioned class 25 have the recognized disadvantage that the periods during which the material is subjected to the mixing action by which the finely ground ore-pulp is impregnated with air and one or more frothing agents, is insufficient to produce a clean separation of 30 the valuable constituents of the ore from the worthless gangue and that in consequence retreatment of the residue is imperative to save the desired percentage of values contained in the pulp.

The second class of flotation processes, while superior to those of the first class, in that the intermixing action may be prolonged until a thorough emulsification of the 40 ore-pulp, air and frothing agent is obtained, are objectionable by reason of the loss of time between the intermittent treatments which naturally results in reducing the capacity of the plant and increasing the cost 45 of operating the same.

It is the primary object of the present invention to provide a method of ore separation in which a continuous feed and continuous discharge are combined with a prolonged treatment of the material during 50 periods of variable pre-established lengths.

Another object of the invention is to provide for the improved separation process, an apparatus which being automatic in its 55 action, requires but little attention, and still a further object of the invention resides in

providing means for introducing air into the material under treatment.

The above and other objects, all of which will fully appear in the course of the following description, I attain by providing a plurality of separated units which by means of an automatic feed distributing mechanism are successively filled with ore-pulp together with a suitable frothing agent.

65

The froth produced in the various units is as usual collected by means of an overflow at the top thereof and the gangue settling out of the material under treatment is discharged by an automatic contrivance which 70 operates in conjunction with the feeding mechanism.

The automatic devices above referred to are relatively arranged so that one of the units of the series is emptying while the preceding one which had previously been emptied, is being supplied with fresh pulp and while the contents of the remaining units of the series are being subjected to the frothing action which preferably consists in beating 75 volumes of air continuously entering the units, into the pulp by mechanical agitation.

A frothing agent, such as oil, is introduced into the pulp by any suitable means either before or after it is fed into the containers 80 and flushing water may if so desired be injected into the same to expedite the discharge of gangue.

It will be seen from the above that my improved method consists briefly in dividing 85 the material under treatment into a number of separated portions which under control of an automatic mechanism for the periodic feed of pulp and discharge of gangue, are subjected to the frothing treatment during 90 periods sufficiently long to insure a clean separation of the values contained in the ore-pulp from the gangue, it being understood that the construction of the automatic mechanism permits of certain adjustments 95 100 by which these periods may be shortened or extended within determinate limits.

My improved method thus combines all the advantages of the continuous and intermittent processes without any of the objectionable features hereinbefore referred to.

In the accompanying drawings in the various views of which like parts are similarly designated,

Figure 1 represents a sectional plan view 110 of an apparatus suitable for use in the practice of my improved method of ore separa-

tion, taken on the plane of the line 1—1, Fig. 2; Fig. 2, a vertical section along the line 2—2, Fig. 1, and

Fig. 3, a horizontal section taken along the line 3—3, Fig. 2.

The apparatus in its preferred form as shown in the drawings comprises a series of upright cylindrical containers 2 which are arranged in a circle in contiguous relation to each other.

A vertical shaft 3 whose axis passes through the center of the circle in which the axes of the containers are disposed, is mounted for rotation in a step-box 4 and carries adjacent its upper end, a worm-wheel 5 which through the intermediary of a worm 6 is operatively connected with a conveniently located source of power.

The shaft extends loosely through the hub 20 of a gear-wheel 7 which is mounted for rotation upon a bearing 35 in engagement with a driving pinion 36 and which meshes with pinions 8 on tubular shafts 9 which are suspended from bearings on frames 10 supported upon the containers.

The shafts 9 whose axes are coincident with those of the containers in which they are suspended, carry at their lower ends, agitating paddles 12 which extend radially 30 above the bottom surfaces of the containers and which are provided with downwardly slanting faces to assist in moving the contents of the containers toward central outlets 13 in their slightly sloping bottom surfaces.

The tubular shafts are connected with a source of air-supply by a pipe 14 provided with branches 15 which connect with the rotating shafts by means of stuffing boxes 16.

The containers have adjacent their upper 40 edges interiorly disposed launders 17 for the overflow of froth produced in the flotation process in which the apparatus is employed.

Circular, perforated water-pipes 18 may be placed above the different launders for 45 the purpose of breaking the foam or froth as it overflows the peripheral edges thereof, and each launder has a discharge spout which connects with a conveniently disposed receiver not shown in the drawings.

Placed concentrically around the driving shaft 3 is an annular feed-launder 19 which is divided into compartments 20 which in number and relative positions correspond with the series of containers.

Each compartment has an outlet-conduit 21 which connects with the respective container at a point below its overflow-launder, and the bottom of each compartment slopes toward its outlet to facilitate the outflow of 60 material under treatment.

In the operation of the machine, ore-pulp is fed into the compartments of the launder 19 by means of a hopper 22 which is fixed on the shaft 3 above the launder and which at 65 the lower end of its sloping bottom has a

spout 23 for the discharge of its liquid contents.

The flow through the hereinbefore referred to outlets 13 in the bottoms of the containers, is controlled by rotary plug-valves 24 in housings 35 which are fixed beneath the containers in permanent connection with their outlets.

The valves which normally are in a closed position, are intermittently opened during 75 predetermined periods by the action of a pair of tappet-arms 25 on the shaft 3, which during their rotary motion with the shaft, engage projections 26 formed at quadrant points of cam-wheels 27 mounted on the 80 valve-stems 28.

The discharge of material from the containers may be expedited by an influx of water through pipes 29 which enter the containers at points adjacent to and below their 85 peripheral overflow launders.

Inasmuch as the supply of water must be concurrent with the discharge of the gangue through the opened outlets of the containers, valves 30 which normally obstruct the flow 90 of water from a manifold 31 into the pipes 29, are connected for synchronous movement with the discharge valves of the respective containers as shown in the drawings.

In the operation of the apparatus, the 95 rotating wheel 7 imparts a comparatively rapid rotary motion to the shafts of the agitating devices, ore-pulp contained in the hopper is together with a suitable frothing agent, fed successively into the compartments of the feed-launder which discharge into the corresponding containers, and air is admitted to the tubular shafts 9 which are open at their lower ends for the injection of air into the contents of the containers.

The violent agitation of the pulp in the containers and the simultaneous aeration of the same, produce a froth composed of bubbles of oil and air in which the sulfid particles of the ore are entrapped.

The froth rising to the surface of the material overflows into the peripheral launders of the containers while it is being broken by the water emitted through the perforations of the circular pipes 18.

After the contents of each container have thus been treated during a pre-established period, sufficient to separate all or most of its sulfid particles from the gangue contained in the ore, the valve controlling the 120 respective outlet is opened while water is admitted to the upper portion of the container past the simultaneously opened valve 30.

After a predetermined interval during 125 which the container is entirely emptied, its valve is closed and a new charge of pulp is fed into the container from the corresponding compartment of the launder.

The coöperating elements of the present 130

invention are arranged so that while one container is being emptied in the above described manner, the flotation process is continuously carried on in all the other containers of the series, with the exception of that preceding the emptying one, with reference to the direction of rotation of the driving shaft, which is being supplied with fresh pulp from the corresponding compartment of the launder.

In this manner each container is intermittently emptied and refilled at predetermined intervals which may be varied by accelerating or retarding the rotation of the driving shaft which by the action of its radial arm upon the cams of the valve-stems, opens and closes the valves of the different containers in regular succession.

The primary advantage obtained in the operation of the apparatus is that the flotation process is carried on to the desired extent without interruption, in a space which need not exceed that occupied by an ordinary flotation tank in which the process must necessarily be periodically discontinued for the discharge of gangue and supply of fresh pulp.

Another advantage of the invention is that the apparatus is automatic in its action and requires little or no attention while in operation.

The supply and discharge to and from the series of containers is continuous, the pulp-level in the containers is constant during the whole period of treatment and this treatment-period can be varied to suit the nature of the ore by changing the speed of rotation of the driving shaft.

It will be understood that variations in the construction and relative arrangement 40 of the coöperative elements comprised in the ore-treating apparatus as above-described and shown in the drawings, may be resorted to within the spirit of my invention as set forth in the following claims:

1. Ore separating apparatus comprising a series of tanks each having an outlet, valves controlling said outlets, mechanism to intermittently open and close said valves, including driven members in circular arrangement separately connected with the valves, and a rotary driving member acting successively upon said driven members, and valves controlling a supply of liquid to said tanks, connected to move in conjunction with 55 the first-mentioned valves.

2. Ore separating apparatus comprising a series of tanks each having an outlet for settling matter, valves controlling said outlets, mechanism to intermittently open and 60 close said valves, including driven members in circular arrangement, separately connected with the valves, a rotary shaft, and a driving member on said shaft acting successively upon said driven members, a feed- 65 launder divided into compartments which are separately connected with the tanks, and a feed-hopper on the shaft having an outlet to supply material successively to the compartments of said launder.

In testimony whereof I have affixed my signature in presence of two witnesses.

THOMAS J. PENNINGTON.
